Primary Examiner — Mimosa De

(74) Attorney, Agent, or Firm — Jeffrey G. Sheldon; Cislo & Thomas LLP

(57) CLAIM

The ornamental design for a chair, as shown and described.

DESCRIPTION

FIG. 2 is a front elevation view of the chair shown FIG. 1; FIG. 3 is a rear elevation view of the chair shown in FIG. 1; FIG. 4 is a right side elevation view of the chair shown in FIG. 1, wherein the left side elevation view is a mirror image;

FIG. 5 is a top plan view of the chair shown in FIG. 1; and, FIG. 6 is a bottom plan view of the chair shown in FIG. 1. All portions of the drawings shown in dashed lines are for illustrative purposes only and form no part of the claimed design.

1 Claim, 6 Drawing Sheets
